Primary Examiner — Paula Allen Greene(74) *Attorney, Agent, or Firm* — Drinker Biddle & Reath LLP(57) **CLAIM**

We claim the ornamental design for a headphone, as shown and described.

DESCRIPTION

FIG. 1 is a lower-left-rear perspective view showing the design.

FIG. 2 is an upper-left-rear perspective view thereof.

FIG. 3 is a front view thereof.

FIG. 4 is a rear view thereof.

FIG. 5 is a left-side view thereof.

FIG. 6 is a right-side view thereof.

FIG. 7 is a top view thereof; and,

FIG. 8 is a bottom view thereof.

The broken lines depict environment that forms no part of the claimed design.

1 Claim, 8 Drawing Sheets(56)
